PORTABLE PERSONNEL CARRIER FOR PICKUP TRUCKS

Kenneth G. Foster, Box 215, North Bonneville, Wash.

Filed Jan. 27, 1964, Ser. No. 78,362

Term of patent 14 years

(Cl. D14—3)

FIG. 1

FIGURE 1 is a rear elevational view of a portable personnel carrier for pickup trucks embodying my new design;

I claim:

The ornamental design for a portable personnel carrier for pickup trucks, as shown and described.
